UNITED STATES PATENT OFFICE.

EDWARD C. SMITH, OF CANTON, OHIO.

DESIGN FOR A VAPORIZER FOR INCANDESCENT LAMPS.

SPECIFICATION forming part of Design No. 34,821, dated July 23, 1901.

Application filed June 15, 1901. Serial No. 64,761. Term of patent 7 years.

To all whom it may concern:

Be it known that I, EDWARD C. SMITH, a citizen of the United States, residing at Canton, in the county of Stark and State of Ohio, have invented and produced a new and original Design for a Vaporizer for Incandescent Lamps, of which the following is a specification, reference being had to the accompanying drawings, forming part thereof.

10 Figure 1 is a side elevation illustrating my new design. Fig. 2 is an edge view.

As shown in the drawings, the leading or material feature of my design consists of the straight portion 1, having extended from one end thereof the curved portion 2, said curved portion being continued past the straight portion 1 and bent to form the curved portion 3, said curved portion terminating at a point

between the curved portions 2 and 3, said curved portions lapped after each other, as 20 illustrated at 4, Fig. 1, and the open spaces 5, located between the open spaces 6 and 7 of the curved portions 2 and 3.

Having fully described my invention, what I claim, and desire to secure by Letters Patent, is—

The design for a vaporizer for incandescent lamps, as herein shown and described.

In testimony that I claim the above I have hereunto subscribed my name in the presence 30 of two witnesses.

EDWARD C. SMITH.

Witnesses:

J. A. JEFFERS,
F. W. BOND.
